UNITED STATES PATENT OFFICE.

THOMAS WIGSTON KINGLAKE CLARKE, OF SURBITON, ENGLAND.

AERONAUTICAL MACHINE.

996,061.

Specification of Letters Patent. Patented June 27, 1911.

Application filed July 11, 1908. Serial No. 443,032.

To all whom it may concern:

Be it known that I, THOMAS WIGSTON KINGLAKE CLARKE, of St. Catherines, Maple Road, Surbiton, in the county of Surrey, 5 England; a subject of the King of Great Britain and Ireland, have invented certain new and useful Improvements in Aeronautical Machines, of which the following is a specification.

10 This invention relates to machines for traversing the air, and consists in certain improvements whereby adjustments for securing accuracy of balance, both in a longitudinal and in a transverse direction are facilitated; and whereby the exposed parts are rendered capable of yielding on contact with the ground or other obstacle and the risk of breakage is diminished.

20 In the accompanying drawings which illustrate, by way of example, a machine embodying my improvements, Figures 1, and 2, are plans respectively of the top and of the underside of the machine. Fig. 3, is a rear elevation of the machine. Fig. 4, a section on the line $x-x$ in Fig. 1. Fig. 5 is a view of one of the propeller blades. Fig. 6 is a detail on an enlarged scale showing the manner of mounting the propeller. Fig. 7 is a transverse section of one of the planes.

30 The type of machine to which my present improvements are for the most part applicable consists of a double bow frame a , furnished at one end with a propeller b , and having as supporting surfaces two transverse planes c c' , which are by preference slightly bent upward on the opposite sides of the machine. The thickest portion of each plane is immediately behind the leading edge as shown more clearly in Fig. 7, 40 and the underside is by preference slightly hollow. The forward supporting surface c is smaller in comparison with the after surface c' .

45 Assuming a screw to be employed for propelling the apparatus, there is a tendency for the latter to tilt laterally owing to the reaction of the propeller. I counteract this tendency by setting the supporting surfaces or one of them out of center with relation to the machine; the aggregate supporting surface on one side of the longitudinal center of the machine being, under such circumstances, somewhat greater than that on the 55 opposite side of the center line, this difference being capable of ready adjustment. In

the same manner, the direction of flight may be varied and controlled.

For securing the supporting surfaces to the frame I employ wire clips d each of which is in the form of an elongated loop 60 bent laterally. The opposite extremities d , d' , of the loop engage beneath the frame, a , while the central portions project above the frame and form bars beneath which the planes c , c' may be slipped. With the aid of 65 such clips d , the planes may be held sufficiently firmly upon the frame a for the purpose of flight; but in the event of either extremity of the supporting surface c or c' coming into violent contact with the ground 70 or other obstacle, the clips d permit the same to yield and avoid injury. According to a modified form of attachment, as shown applied to the after plane c' , a curved 75 spring-clip e is pivoted at its center to the plane; this clip being passed between the sides of the frame and its opposite extremities brought beneath the latter. Such methods of mounting the supporting surfaces upon the frame also facilitate the adjustment of the former upon the latter in a fore and aft direction.

With the same object, the screw-propeller is slipped upon a wire or other suitable holder b' and held in position by friction. 85 In the event of either of the blades coming into forcible contact with the ground, the entire propeller becomes unshipped without suffering injury.

In constructing a propeller for a model or experimental machine, I form the blades b^2 b^2 separate, each blade having a flattened stem or shank b^3 . The stem has a twist imparted to it; and when two such twisted stems are placed face to face and bound or otherwise fastened together a two-bladed propeller results, having the blades set at the proper angle, according to the pitch desired. I prefer to make the leading edge of 90 the blade straight, the major portion of the surface lying behind the axis of the stem when prolonged. The working face of the propeller-blade is by preference slightly concave and the back of the blade convex. 95

For enabling the screw-propeller to be 100 started after the machine has left the land, I mount a pin f in one or two eyes f' , the extremity of the pin projecting into the path of the screws b . This pin is attached by 105 means of a line f^2 to the wrist of the user, 110

and is thereby withdrawn after the machine has been launched in the direction of its intended flight; the propeller being thus released and coming into operation before the machine falls to the ground. Where twin-propellers are employed, each is controlled in the same manner; and the two fixing pins may be attached to the same wrist line.

The thrust block for the propeller consists of a plate *g* fastened to the underside of the frame *a*, (see Fig. 2), and bent upward, the propeller shaft passing through the bent portion.

The propeller, in the model form shown, is driven by twisted rubber bands *h*, secured to the forward part of the frame and to the propeller shaft *b'*.

What I claim as my invention and desire to secure by Letters Patent, is:—

1. An aeronautical machine comprising two transversely arranged supporting surfaces, placed fore and aft of the machine, and having the area of the forward surface small in comparison with that of the after

surface, the position of either of the said surfaces being adjustable, both laterally and rotatively, in relation to the body of the machine.

2. In an aeronautical machine, the combination with a frame, of supporting surfaces arranged fore and aft of the frame and clips arranged to adjustably and detachably secure the supporting surfaces to the frame.

3. In an aeronautical machine, the combination with a frame, of a screw propeller, a supporting surface arranged transversely of the frame and laterally out of center in relation to the machine whereby the lateral tilting tendency due to the propeller is counteracted.

In testimony whereof I have signed my name to this specification in the presence of two subscribing witnesses.

THOMAS WIGSTON KINGLAKE CLARKE.
